CLAIM

The ornamental design for light dimmer module, as shown and described.

DESCRIPTION

FIG. 1 shows a front, right and top perspective view of the light dimmer module with a plug and socket shown as environment in broken lines;

FIG. 2 shows a front elevation view of the light dimmer module with a socket shown as environment in broken lines;

FIG. 3 shows a rear elevation view of the light dimmer module with a plug shown as environment in broken lines;

FIG. 4 shows a right side elevation view of the light dimmer module with a plug shown as environment in broken lines, the left side elevation view of the light dimmer module being a mirror image thereof;

FIG. 5 shows a top plan view of the light dimmer module with a plug shown as environment in broken lines, the bottom view of the light dimmer module being a mirror image thereof; and,

FIG. 6 shows a rear, left, and bottom perspective view of the light dimmer module with a plug shown as environment in broken lines.

The broken lines in all FIGs. illustrate environment of the light dimmer module that form no part of the claimed design.
